(57) **CLAIM**

The ornamental design for a tank cover, as shown and
described.

DESCRIPTION

FIG. 1 is a front view of the tank cover of the present
invention attached to a tank, the rear, left and right views
being the same;

FIG. 2 is a top plan view of the invention disclosed in FIG.
1; and,

FIG. 3 is a bottom plan view of the invention disclosed in
FIG. 1.

The broken line showing of a tank in FIGS. 1, 2 and 3 is for
illustrative purposes only and forms no part of the claimed
design.
